UNITED STATES PATENT OFFICE

JOEL B. WELLS, OF STRATFORD, PENNSYLVANIA

DESIGN FOR A SMOKER'S DEVICE

Application filed October 21, 1930. Serial No. 37,337. Term of patent 3½ years.

To all whom it may concern:

Be it known that I, JOEL B. WELLS, a citizen of the United States, residing at Stratford, in the county of Chester, State of Pennsylvania, have invented a new, original, and ornamental Design for Smoker's Device, of which the following is a specification, reference being had to the accompanying drawings, forming part thereof.

Fig. 1 is a view in perspective from a point oblique to the front showing my new design. Fig. 2 is a view in perspective from a point directly in front.

The opposite side of the article from that shown in the drawings and the back portion are plain.

I claim:

The ornamental design for a smoker's device as shown and described.

JOEL B. WELLS.
